* cited by examiner

Primary Examiner—Stella M. Reid*Assistant Examiner*—Elizabeth J Oswecki(74) *Attorney, Agent, or Firm*—Raymond M. Galasso;
Galasso & Associates LP(57) **CLAIM**

The ornamental design for a lighted turkey, as shown and described.

DESCRIPTION

FIG. 1 is a perspective view of a lighted turkey showing my new design; and,

FIG. 2 is a front view thereof, the back view being a mirror image thereof.

All surfaces not shown form no part of the claimed design.
